UNITED STATES PATENT OFFICE.

JOHN E. MILSON, OF WATERTOWN, MASSACHUSETTS, ASSIGNOR OF ONE-HALF TO
JOHN J. BURNS, OF BOSTON, MASSACHUSETTS.

CHEMICAL-MIXING APPARATUS.

1,267,102.

Specification of Letters Patent. Patented May 21, 1918.

Application filed November 13, 1916. Serial No. 130,982.

To all whom it may concern:

Be it known that I, JOHN R. MILSON, a citizen of the United States, and resident of Watertown, in the county of Middlesex and 5 State of Massachusetts, have invented certain new and useful Improvements in Chemical-Mixing Apparatus, of which the following is a specification.

This invention relates to apparatus for 10 and process of mixing together chemicals of different natures, not ordinarily capable of ready mixing, and the object of the invention is to provide simple and effective means for connecting a plurality of different chemical containers to a common receptacle, applying 15 heat to each container sufficient to distil off its contents, and to provide means for preventing the discharge of such contents until a predetermined degree of heat or pressure 20 has been generated in each container.

A further object of this invention is to provide a mixing chamber in which the gases are first received from the different containers to be subsequently discharged 25 into a receptacle.

A still further object of the invention is the provision of means in the mixing chamber for agitating and mixing the different gases as distilled and while in a gaseous 30 state.

The invention further consists in providing means for cooling and condensing the mixture after entering the receptacle.

With these and other objects in view, the 35 invention consists of certain novel features of construction, as will be more fully described, and particularly pointed out in the appended claims.

In the accompanying drawings:

40 Figure 1— is a diagrammatic view illustrating my improved mixing apparatus the cooling chamber being partly broken away.

Fig. 2— is a sectional view showing one form of automatically operated relief valve.

45 In carrying out my invention, I have provided a plurality of containers 10 which carry the different chemicals. One side of each container is provided with a sight gage 11 for determining the height of the liquid therein and a thermometer 12 is also provided to indicate the temperature to which the container is being heated. Each of these 50 containers rests upon a base or frame 13 in which is located a gas burner 14 or other 55 means for heating the container. The gas is

supplied to the burner through the pipe 15 and controlled by the valve 16, whereby the temperature in each container or tank may be raised as rapidly or as slowly as desired. This means of regulating the heat is 60 found to be of great importance as the chemical solutions in the different containers often require different degrees of heat in order to bring them to the boiling or melting point and by the use of these adjustable 65 valves the heat may be so regulated under each container that all may be brought to the desired temperature at substantially the same time, so that all will discharge simultaneously into a common mixing chamber 21. 70

These containers are connected through pipes 17, 18, 19 and 20, respectively, to this mixing chamber and valves 22 are placed in each of these pipes which may be controlled by the adjustable weight 23 to hold back the 75 pressure generated in the different receptacles until it is raised to a predetermined degree after which these valves open automatically and permit the volatile contents of the containers to be carried over into the 80 mixing chamber.

In some cases it is found in the distilling of certain groups of chemicals that it is necessary to provide means for agitating the gases in the mixing chamber in order to insure a complete mixing of the same. One 85 means of producing this mixing effect is herein illustrated, which comprises a shaft 24 set longitudinally in the mixing chamber and provided with paddles or fan blades 90 25, the whole being inserted through the plugged end 26, the shaft being driven through the pulleys 27 and 28 by the motor 29, whereby when the shaft is rapidly rotated the gases from opposite ends of the 95 chamber are driven toward each other to insure a thorough mixing of the same.

This mixing chamber is connected by pipe 30 in the air-tight reservoir 31 which is provided with an outlet 32 near its bottom 100 through which the cooled and condensed contents may be drawn.

In order to provide suitable means for quickly cooling the contents of this receptacle, I have mounted the same in a casing 105 33, which is provided with a tight cover 34 secured in position by wing nuts 35. An inlet pipe 36 is screwed into the upper portion of this casing through which the cooling water enters and after circling around 110

through the casing it is discharged through the outlet pipe 37 on the opposite side thereof.

The flow from the mixing chamber to the receptacle may be controlled when desired by the valve 38 so that the passage of the gas from the mixing chamber to the receptacle may be delayed if desired until the gases have been thoroughly mixed in the

10 chamber.

It is desirable to have means for locking the valves 22 open, after they have been actuated by the pressure in the containers, so that after the containers have once been 15 brought to a predetermined temperature these valves will open and stay open to permit the entire contents to be discharged over into the mixing chamber. In order to accomplish this, I have provided a spring 20 latch 39 which will enter the notch 40 in the hub of the lever arm 41 and retain the valve in open position after having been opened until again released to again repeat the operation. The weight 23 on the valve 25 may be adjusted to permit the valve to operate by a predetermined pressure.

I have shown and described one form of relief valve but any other suitable form of valve may be employed for releasing the 30 contents of the containers after having been heated to the desired temperature.

Having thus described one illustrative embodiment of my invention and the best mode known to me of carrying out my 35 method I desire it to be understood that although specific terms are employed they are used in a generic and descriptive sense and not for the purpose of limitation, the scope of the invention being defined and limited 40 by the appended claims.

I claim:

1. A chemical mixing apparatus comprising a plurality of chemical containers, a mixing chamber with which all of said containers are connected, means for heating 45

each of said containers for the purpose of distilling off its contents, and automatic valves for controlling the flow from the containers into said mixing chamber.

2. A chemical mixing apparatus comprising 50 a plurality of chemical containers, a mixing chamber with which all of said containers are connected, means for heating each of said containers for the purpose of distilling off its contents, and pressure operated valves mounted on the tops of said containers and controlling the flow from the containers into the mixing chamber.

3. A chemical mixing apparatus comprising 55 a plurality of chemical containers, a mixing chamber with which all of said containers are connected, means for heating each of said containers for the purpose of distilling off its contents, automatic valves for controlling the flow from the containers 60 into said mixing chamber, and means for automatically locking said valves in open position.

4. A chemical mixing apparatus comprising 70 a plurality of chemical containers, a mixing chamber with which all of said containers are connected, means for heating each of said containers for the purpose of distilling off its contents, automatic valves for controlling the flow from the containers 75 into said mixing chamber, and a condensing reservoir connected with the mixer to receive gases discharged from said mixer.

5. A chemical mixing apparatus comprising 80 a plurality of chemical containers, a mixing chamber with which all of said containers are connected, means for heating each of said containers for the purpose of distilling off its contents, automatic valves for controlling the flow from the containers 85 into said mixing chamber, and means for agitating the gases within said mixing chamber.

In testimony whereof I affix my signature.

JOHN R. MILSON.
